DESIGN FOR AN OIL WELL PUMPING UNIT

Luther A. Blackburn, Lynwood, Calif.

Application September 18, 1946, Serial No. 133,393

Term of patent 14 years

(Cl. D65—1)

To all whom it may concern:

Be it known that I, Luther A. Blackburn, a citizen of the United States, residing at Lynwood, in the county of Los Angeles and State of California, have invented a new, original, and ornamental Design for Oil Well Pumping Unit, for which the following is a specification, reference being had to the accompanying drawing, forming part thereof, in which:

Fig. 1 is a side elevation of an oil well pumping unit showing my new design;

Fig. 2 is an end elevation;

Fig. 3 is a top plan view of the unit.

I claim:

The ornamental design for an oil well pumping unit, as shown.

LUTHER A. BLACKBURN.
